UNITED STATES PATENT OFFICE.

WILLIAM H. BROWN AND WILLIAM H. DE LONG, OF WORCESTER, MASSACHUSETTS; SAID DE LONG ASSIGNOR TO SAID BROWN.

TAPE-MEASURE.

SPECIFICATION forming part of Letters Patent No. 578,205, dated March 2, 1897.

Application filed March 22, 1895. Serial No. 542,863. (No model.)

To all whom it may concern:

Be it known that we, WILLIAM H. BROWN and WILLIAM H. DE LONG, citizens of the United States, residing at Worcester, in the county of Worcester and State of Massachusetts, have invented a new and useful Improvement in Tape-Measures, of which the following is a specification, accompanied by drawings forming a part of the same, in which—

Figure 1 represents a side elevation of a tape-measure embodying our invention. Fig. 2 is a side elevation showing the opposite side to that represented in Fig. 1. Fig. 3 is a side elevation similar to that represented in Fig. 2, but having the case shown in sectional view, the side of the case next the beholder having been removed. Fig. 4 is a sectional view on line 4 4, Fig. 1. Fig. 5 is a central sectional view on line 5 5, Fig. 1. Fig. 6 represents a detached view of the barrel upon which the tape is wound and represented in sectional view on line 6 6, Fig. 3; and Fig. 7 represents a portion of the rim of the barrel with the free end of the steel blade which forms the brake, said blade being shown in central sectional view.

Similar letters refer to similar parts in the different figures.

Our invention relates more particularly to that class of tape-measures designed for use by surveyors and civil engineers; and it has for its object to produce a more convenient case, in which the measuring-tape is wound and held, which will readily enable the desired tension to be applied to the tape-measure when the case is held in the hand, said case being cast of metal and preferably in a single piece; and our invention has also for its object to provide means for checking the rotation of the barrel upon which the measuring-tape is wound, for controlling the measuring-tape as it is wound upon the barrel, and also to provide means for fastening the end of the tape to the winding-barrel, and for fastening the free end of the tape when it is wound upon the barrel, and these objects are attained by means of the construction and ar-

angement of parts as hereinafter described, and shown in the accompanying drawings.

Referring to the drawings, A denotes a metallic shell or case, preferably of cast metal and constructed with its handle A' in a single piece with the case. The case A comprises a central stud A², radiating spokes A³, uniting the central stud with a circular rim A⁴, ring A⁵, and short spokes A⁶, connecting the ring A⁵ with the outer circular rim A⁴. Upon one side the rim A⁴ is extended to form a curved handle A', said handle having its curvature lying in the plane of rotation of the barrel upon which the tape is wound and adapted to be held in the hand and allow a direct pull upon the free end of the measuring-tape to be conveniently resisted by the person holding the case, and upon the under and farther side of the case from the handle at a point about one-third of its circumference the rim A⁴ is extended to form a spout A⁷, so arranged with reference to the handle A' that when the handle is held in the hand the measuring-tape can be drawn through the spout A⁷ in a direction tangential to the coil wound upon the rotating barrel and in a nearly direct line with the handle A' and delivered from the case through the opening A⁸ in the end of the spout A⁷.

The central stud A² forms a pivot around which the rotating barrel B turns, on which the measuring-tape B' is wound. The barrel B consists of a circular web B², provided with a concentric inner flange B³, inclosing the central stud A², and a concentric outer flange B⁴, upon which the tape is wound. The web B² is provided on its outer surface with the projecting lugs B⁵, to which is hinged a lever B⁶, carrying in its end a stud B⁷, upon which is journaled a roll B⁸, forming a handle which is held upon the stud B⁷ by a screw B⁹.

The roll B⁸ is provided with an enlarged or flaring base B¹⁰, so that when the roll is seized by the tips of the thumb and fingers they will be prevented from coming in contact with the lever B⁶. The lever B⁶ extends a short distance beyond the lugs B⁵ and preferably carrying rolls B¹¹, rotating upon pins B¹², held in the lever B⁶, and bearing against blade-

springs B^{13} , which are secured to the under side of the web B^2 by screws B^{14} . Each of the blade-springs B^{13} is bent near its free end, as at B^{15} B^{15} , with the bent sections extending through openings B^{16} B^{16} in the web B^2 , bringing the blade-springs into contact with the rolls B^{11} , so the tension of the blade-springs B^{13} will hold the lever B^6 in the position shown in Fig. 1, or in the extended position indicated by the broken lines B^{17} , Fig. 1.

The outer flange B^4 , upon which the tape is wound, is cut apart, with the end B^{18} bent in toward the center of the barrel and provided with a spur B^{19} , which enters a hole in the end of the tape, thereby attaching the tape to the barrel and permitting it to be readily detached when unwound by lifting the perforated end of the tape off the spur B^{19} .

Friction is applied to the outer surface of the tape wound upon the barrel by means of a blade C , pivoted at one end about a screw C' , held in the curved handle A' , and having its free end resting upon the surface of the tape as it is wound upon the barrel with a pressure due to the tension of a blade-spring C^2 , attached to the blade C and bearing against the inner surface of the case. When the tape has been unwound from the barrel B , the free end of the blade C drops into the notch formed by the bent end B^{18} of the flange B^4 striking the end B^{20} , thereby checking the further rotation of the barrel and allowing the tape to be drawn taut. It is, however, frequently necessary to check the rotation of the barrel B , in order to allow the tape to be drawn taut, when only a portion of the tape has been unwound from the barrel. This is accomplished by providing the ring A^5 with a series of notches A^9 and pivoting a pawl D on the outer side of the web D^2 , adapted to engage one of the notches A^9 and hold the barrel from rotation. The pawl D is attached to a spindle D' , rotating in a boss D^2 , Fig. 4, projecting from the under side of the web B^2 . The inner end of the spindle is enlarged and provided with flattened sides D^3 , against which the end of the spring D^4 bears, so as to hold the pawl D either in engagement with one of the notches A^9 , as represented in Fig. 1, or in the position indicated by the broken lines D^5 , Fig. 1.

The end of the tape B' is provided with a ring E , larger in diameter than the width of the opening A^8 , and when the tape has been wound upon the barrel B the ring E is fastened by being inserted in the semicircular notch E' in the rim A^4 and by being drawn into the semicircular notch E^2 in the end of the spout and held therein by the winding up of the tape, the pawl D and notches A^9 being suitably arranged, so that when the ring E is drawn into the notch E^2 the pawl D will engage one of the notches A^9 and hold the tape taut.

When it is desired to unwind the tape, the

pawl D is pushed out of engagement with the notch A^9 into the position indicated by the broken lines D^5 , Fig. 1, in which position the pawl will be held by the tension of the spring D^4 , thereby allowing the tape to be loosened and the ring E to be released. 70

The web B^2 is provided with a hole F to receive the roll B^8 when the lever B^6 is folded upon the barrel, and when the tape requires to be wound upon the barrel B the lever B^6 75 is extended into the position shown by the broken lines B^{17} . The barrel B is held upon the central stud A^2 by means of a washer G and a screw G' , thereby allowing the barrel to be readily removed. 80

We are aware that it is not new to provide a case or frame containing a tape-measure with a projecting handle, and we do not claim such, broadly.

We provide the case with a curved handle 85 arranged opposite to the delivery of the tape, so the strain upon the tape in drawing it taut will be received as a direct pull upon the hand.

What we claim as our invention, and desire 90 to secure by Letters Patent, is—

1. In a tape-measure the case, or shell A comprising the central stud A^2 , rim A^4 , ring A^5 uniting spokes A^3 connecting said central stud and said rim, short spokes A^6 connecting said rim and said ring A^5 , a barrel carried on said central stud and means for connecting said barrel and said ring, substantially as described. 95

2. In a tape-measure, the combination of a case or shell comprising a ring A^5 having notches A^9 , a rotating barrel held in said case and a pawl pivoted on said barrel and adapted to engage said notches and check the rotation of said barrel, substantially as described. 100

3. In a tape-measure, the combination of a case or shell, a barrel held in said shell having a flange B^4 bent as at B^{18} , a spur B^{19} and a tape having a perforated end detachably engaging said spur, substantially as described. 105

4. In a tape-measure, the combination of the case or shell, a barrel rotating in said case, lever B^6 hinged to said barrel rolls B^{11} carried by said lever, blade-springs B^{13} attached to said barrel and bearing against said rolls, stud B^7 carried by the end of said lever and a roll B^8 provided with an enlarged or flaring base B^{10} , substantially as described. 110

5. In a tape-measure, the combination of a case or shell, a handle projecting therefrom, a rotating barrel held in said case, a blade pivoted in said handle and having its free end arranged to bear upon the tape as it is wound upon said barrel, and a spring applied to said blade to press it upon the tape, substantially as described. 115

6. In a tape-measure, the combination of a case or shell, a handle projecting from the side of said case, a rotating barrel held in said case and provided with a notch in its pe- 120

riphery, a blade pivoted in said handle with its free end arranged to bear upon the tape as it is wound upon said barrel and to engage said notch as the tape is unwound and a spring applied to said blade, substantially as described.

7. In a tape-measure, the combination with a case or shell provided with the notches E' and E², of a rotating barrel held in said case, 10 a tape wound upon said barrel, a ring carried

by the free end of said tape adapted to lie in said notches, and means for holding said barrel from rotation, substantially as described.

Dated the 28th day of February, 1895.
